UNITED STATES PATENT OFFICE.

FRANK HURBERT ARMSTRONG, OF AUBURN, NEW YORK, ASSIGNOR TO CORONA TYPE-WRITER COMPANY, INC., OF GROTON, NEW YORK, A CORPORATION OF NEW YORK.

TYPEWRITING MACHINE.

Application filed September 30, 1918. Serial No. 256,195.

To all whom it may concern:

Be it known that I, FRANK H. ARMSTRONG, a citizen of the United States of America, and a resident of Auburn, county of Cayuga, 5 State of New York, have invented certain new and useful Improvements in Typewriting Machines, of which the following is a full and clear specification.

This invention relates to that class of 10 paper-feeding devices in which is employed a plurality of rolls spring-pressed against a cylindrical platen, means being provided for retracting the rolls downwardly away from the platen to release the paper, and one of 15 the main objects of the present invention is to so construct the feed-roll supporting and actuating devices that they will be capable of being stamped up from sheet-metal, so as to thereby greatly reduce the 20 amount of machine work usually required to properly fit and assemble the parts, as more fully hereinafter set forth. This invention has other important objects in view 25 which will appear in the course of this specification.

In the drawings—

Fig. 1 is a perspective view of mechanism embodying the preferred form of my invention, the platen-roll being omitted from the 30 drawing and one of the platen-supporting members being broken away for the purposes of better illustration;

Fig. 2 is a vertical longitudinal sectional view on the line 2—2 of Fig. 3;

Fig. 3 is a plan view of the mechanism as it appears in Fig. 1;

Figs. 4, 5, 6 and 7 are vertical cross-sections on the line 4—4 of Fig. 3 showing various positions of the feed-rolls with 40 respect to the platen;

Fig. 8 is a cross-section of the platen-carriage showing in detail the manually-operable releasing-cam devices;

Figs. 9, 10, 11, 12, 13 and 14 are detail 45 views of parts hereinafter specifically described.

Referring to the drawings annexed by reference-characters, 15 designates the platen-carriage provided at each end with 50 an upstanding flange 16 in which the ends of the shaft 17 of the platen 17 are journaled in the usual manner.

Extending between the end-flanges 16, the full length of the carriage, is a sheet-metal 55 bar 18 which constitutes a rock-shaft by

reason of the fact that each of its extreme ends is bent downwardly to form an ear 19, which ear is pivotally supported on a screw-pivot 20 threaded from the outside inwardly through the end-flange 16, the bar being 60 rockable upon these pivots 20. This bar is located behind the platen and at a point about on a horizontal level with the under face of the platen. The rear edge of the bar is bent downwardly to form a longitudinal 65 flange 21 to stiffen the rock-bar, and the front edge of this rock-bar is provided with four forwardly-extending lever-fingers 22, each of which at its extreme forward end is bent downwardly and then upwardly to 70 form a hook 23 which is open at its upper side. This rockable plate-like shaft 18 may be manually rocked by means of a cam-lever 24 pivotally mounted on platen-shaft 17 close to the inner face of one of the end-flanges 16 of the carriage, the cam part of 75 this lever being provided with two working faces 25 and 26, adapted to alternately co-operate with the upper edge of an arm 27 formed integral with the rock-bar 18 and 80 bent to fit flatwise against the adjacent end 16 of the carriage so that its free forward end will lie directly under the two working faces of the cam 24, said arm 27 being normally held up against one or the other of 85 said working-faces 24 and 25 by a retractile spring 28. When the arm 27 lies against the cam-face 25, the rockable bar 18 will be in its normal position, i. e., with its upper face 90 horizontal, and the feed-rolls, as hereinafter described, will be in their normal position against the platen or the work-sheet thereon; but when the cam-lever 24 is turned to swing down the forward end of the arm 27 and thus bring the other-cam face 26 into locking 95 relation with the upper edge of the arm 27, the rockable bar 18 will have its forward edge tilted downwardly and thus, in the manner hereinafter set forth, cause the feed-rolls to be retracted from working position. 100

The feed-rolls 29 are arranged in two sets, one at each side of the mid-length of the platen. Each set consists of a front-shaft 30 and a corresponding rear-shaft 31, each shaft carrying one or more of the feed-rolls 29, two being shown on each shaft in the 105 present structure, a loose spacing-sleeve 32 being arranged between each pair to space them apart. Each of the front-shafts 30 is journaled loosely in upstanding ears 33 110

formed integral with the forward ends of a pair of flat bars 34, and each of the rear-shafts 31 has each of its ends journaled in a pair of upstanding ears 35 formed integrally with the rear end of each of the bars 34, so that each set of rolls forms a substantially rectangular frame consisting of a front-shaft 30, a rear-shaft 31, and the two bars 34 which connect corresponding ends 10 of said shafts. The rear ends of the bars 34 are so located that when the fingers 22 are depressed the lower rounded portions of hooks 23 bear downwardly upon the rear ends of the bars 34 and thus tilt said bars 15 downwardly. In its preferred form, which is that illustrated, I arrange the bent ends of the fingers 22 so that each will lie between a pair of the ears 35 in such position that the shaft 31 will extend through the hook-like part 23 of the finger, the purpose in turning up the extreme end of the finger to form said hook being to engage the front face of the shaft 31 and thus assist in holding the parts in their assembled relation.

25 To assist in holding the shafts 31 against undue endwise movement in their supporting ears 35, I provide the bar 18 with forwardly-extending fingers 36 which are bent downwardly at their forward ends to lie in axial alignment with said shafts, a slight distance from the ends of said shafts. In the present construction, these shafts 31 need only be journaled loosely in the ears 35 so that they will naturally have a slight endwise movement in these ears; it is for this reason that I provide said stop-lugs 36. In this way, I avoid the necessity of providing the shafts 31 with stop-collars adapted to abut against the ears 35. For the same reason, I provide 30 each of the forward ends of the bars 34 with an upstanding stop-lug 37 in position to restrict the endwise movement of the front-shafts 30. It will be observed that the rear portion of the arm 27 is curved or arched 35 upwardly so that the rear feed-roll-shaft forming part of the feed-roll-frame at the right-hand end of the carriage may be readily slipped endwise through the apertures in the ears 35 on the bars 34 in assembling the feed-roll supporting and casting-off mechanism.

50 Each of the rectangular frames of which the parts 34 form the end-bars is supported upon a flat sheet-metal bar 38 whose ends lie loosely flatwise under said bars 34. Each of the flat bars 38 has a pivotal support about midway its length upon a plate 39, which plate is rockably supported at its ends by a pair of laterally-extending arms 40, each 55 of these arms being provided with an integral pivot 41 whose axes are in transverse alignment with each other, said pivots being journaled in upstanding ears 42 struck up from the platen-carriage. The two rocking plates 39 are normally pressed up toward

the platen surface by means of a spring 43 which connects a pair of upstanding arms 44 attached integrally to the pivot-ends of the arms 40, so that said spring constantly tends to rock the bell-cranks formed by the 60 arms 40-44 in a direction to raise the supporting plate 39. It will thus be seen that when the rock-shaft 18 is tilted to have its upper face in horizontal position, the fingers 22 will be in their raised position and the two 65 roller-sets will be free to be pressed up against the platen through the medium of the bars 38 and their spring-actuated connections; and that when said bar 18 is tilted in the manner heretofore described the downwardly-bent ends of the fingers 22 will strike against the rear ends of all the bars 34 and first swing them downwardly far enough to retract the rear feed-rolls 29 but still leave the front feed-rolls in working position. In 70 this initial action the bars 38 pivot on the front-roll-shafts 30 and are depressed bodily against the action of spring 43. A further depression of the fingers 22 will swing the bars bodily downward about the axis of the 75 rock-shaft 18 against the action of spring 43 (and thus bring about a corresponding depression of the forward ends of the bars 34) by the following means: Several (preferably 4) of the ears 35 are each extended upwardly 80 and rearwardly to a point above the upper flat surface of the rock-bar 18, thus forming hook-like levers 45. The initial tilting of the rock-bar 18 and the bars 34 brings the rear extremities of the levers 45 into contact with said rock-bar 18 so that after the rear feed-rolls have been retracted from the platen these levers 45 interlock with the rock-bar 18 in the manner of a knuckle-joint 85 and thereby cause the further tilting of the rock-bar 18 to carry down with it the forward ends of the bars 34, as shown in Fig. 7, in which position the spring 43 is extended 90 to maximum and the rocking supporting plates 39 are pressed down flatwise against the upper surface of the platen-carriage 15. The parts are locked in this off position by means of the cam-face 26 of the cam-lever hereinbefore described; and when the handle-end of the cam-lever is drawn rearwardly, as 95 shown in full lines in Fig. 8, to bring the other cam-face 25 into action, the spring 28 will draw the rock-bar 18 to normal position 100 and thus permit spring 43 to restore all the feed-rolls to working position.

105 The upstanding arms 44 of the bell-cranks are desirably each provided with a series of two or more notches 46 to enable the spring 43 to be connected thereto farther from or nearer to the pivots 41, to thereby vary the leverage exerted by the spring. The bearings 42 for the pivots 41 are desirably stamped up from the body of the platen-carriage, as shown particularly in Fig. 14. The manner 110 of connecting the supporting-plate 39 to the 115

pressure-bar 38 may be greatly varied without departing from my invention, but, for simplicity of manufacture and compactness, I prefer the construction illustrated, in which 5 the plate is provided with a longitudinal slot 47, extending transversely with respect to the platen-carriage, and the bar 38 with a pair of depending hooks 48 which extend through said slot and have their laterally- 10 extending ends engaging the under side of the plate 39, to thereby form virtually a pivotal locking connection between the bar 38 and said plate 39. For the purpose of providing the pressure-bar 38 with a broad 15 bearing upon the rocking-bar 39, said bar is elongated transversely of the platen-carriage (at 49) and the hooks 48 are arranged at the extremities of said transverse extension or enlargement, this enlargement forming 20 virtually a bar lying in the same horizontal plane with the main part of the bar 38 and at right angles thereto. This bar-like enlargement 49 is formed integral with the bar 38, and the hooks 48 at the ends of this enlargement are formed integrally therewith by simply bending down the hook-like ends 25 of the bar. For compactness, it is desirable that when the feed-rolls are thrown downwardly to released position, the rocking- 30 plate 39 will lie directly against or near to the upper surface of the platen-carriage, as shown in Figs. 6 and 7, and, in order that the depending hooks 48 will not interfere with this action, the platen-carriage plate is 35 provided with holes 50 to permit the hooks to pass down through the platen-carriage plate.

It will be observed that the two extremities of each of the bars 38 are bent down- 40 wardly to pass under the bars 34 and that at points coincident with these bent-down ends the platen-carriage is provided with holes 51 to permit these bent ends to pass down through the top-plate of the platen- 45 carriage when the bars 38 are depressed to their lowermost position; in this way, compactness in my device is further provided for.

The sheet-metal paper-guide pan 52 is 50 provided at its forward edge with depending ears 53 which are rigidly fastened to the rear face of the scale-bar 54. The paper-guide is provided at intervals with longitudinal slots 55 through which the feed-rolls 55 extend, and, for the purpose of ensuring a positive movement up and down of the guide in unison with the feed-rolls, I provide the guide at each end with a depending ear 56 for engagement with the adjacent front feed- 60 roll shaft 30, said ear being provided with a hole through which the shaft extends.

It will be observed that the hooks 23 fit loosely between the upstanding ears 35 and that the upwardly-extending extreme ends 65 of these lugs are each tapered upwardly; the

object of this is to avoid clamping against the inside faces of the two upturned lugs and yet maintain a locking relation between the feed-roll-frames and the rock-shaft, whereby the roll-frames will have great freedom in independently adjusting themselves to the work on the platen. It will be observed also that the space between the shaft 70 31 and the upper face of the bar 34 is greater than the thickness of the hook 23, thereby 75 providing for a certain degree of play or lost motion in the connections between the frames and the hooks 23; the object of this is to permit the rear feed-roll-shafts to adjust themselves to inequalities of platen and 80 paper without resistance from the rock-shaft and also to permit endwise tilting of the frames and bars 38 on plates 39 as well as straight up and down movements of the frames and bars 38 against the pressure of 85 plates 39.

It will be observed further that the manner of connecting the forward feed-roll-shafts to the rear feed-roll-shafts and the rear feed-roll-shafts to the rock-shaft holds 90 all the parts securely in position and yet permits a high degree of torsion-like action of the parts to thereby compensate for inequalities of platen or paper.

It will be observed further that my manner of connecting the parts of the feed-roll-frames together and locking them to the rock-shaft avoids the use of rivets and screws or other machined parts and at the same time provides a construction whose parts 95 are so interlocked that the omission of any one part in the particular construction shown would destroy the functions of all the other parts, since the shafts of the rolls not only support the usual feed-rolls but also lock the 100 feed-roll-frames to the releasing rock-shaft at the rear. It will be observed further that the employment of the type of hook shown for connecting the feed-roll-frames through the medium of the feed-roll-shafts to the 105 rock-shaft prevents the forward ends of the feed-roll-frames from swaying or shifting to an undue degree laterally and at the same time keeps the rear feed-roll-shaft square 110 with the feed-roll-frames as well as the rock-shaft, while at the same time this connection between the rock-shaft and the feed-roll-frames allows these frames to oscillate freely on the rear feed-roll-shaft.

One of the objects of this invention is to 115 adapt my device especially for use on compactible typewriters, such, for instance, as the Corona, in which the space between the platen-roll and the top-face of the carriage is so limited that it is difficult to arrange an 120 efficient feed-roll-release or cast-off mechanism in said space. I have designed the preferred form of my mechanism with a view of locating the cast-off devices at the rear of the platen and partly in the bite 125 130

formed between the rear-face of the platen and the top-face of the carriage, none of the parts of this cast-off mechanism being extended into the space between the center 5 of the platen-roll and the carriage-top. In the structure I have illustrated herein, as well as in the several modifications thereof I have disclosed in copending applications, this cast-off or releasing mechanism is so 10 constructed and arranged that it operates by engagement with the rear-edge or part of the feed-roll-frame, that is, the part which projects into the bite between the carriage and the platen, the preferred construction embodying a rock-shaft adapted to be 15 rocked forwardly to first depress the rear feed-roll-shaft and then pry or leverage down the front feed-roll-shaft, a sort of knuckle or rule joint connection being provided between the feed-roll-frame and the rock-shaft to bring about this successive retraction of the rear feed-rolls and the front feed-rolls. In this way, as stated, I avoid 20 locating any of the roll cast-off devices underneath the platen, so that I am enabled to select from a wide range of constructions an efficient mechanism, not being restricted in the selection of the mechanism to such as would be required if the cast-off devices had 25 to be located in the very narrow space between the platen and the carriage.

The nature and scope of the invention having been thus indicated and its preferred embodiment having been specifically 30 described, what is claimed as new is:

1. In a paper feed mechanism, the combination of a platen support, a platen on said support, front and rear feed-roll shafts, transverse members supporting said shafts, 40 manually rockable means adjacent the rear feed-roll shaft and having an up-and-down sliding connection with said shaft and adapted to engage and depress the rear ends of said members when rocked in one direction, means for locking the members to said rockable means to rock as a unit therewith after a preliminary depression of the rear ends of the members, and yieldable means 45 connected with said members for normally holding the feed rolls against the platen.

2. In a paper feed mechanism, the combination of a platen support, a platen on said support, front and rear feed-roll shafts, transverse members supporting said shafts, 55 manually rockable means adjacent the rear feed-roll shaft and having an up-and-down sliding connection with said shaft and adapted to engage and depress the rear ends of said members when rocked in one direction, means for locking the members to said rockable means to rock as a unit therewith after a preliminary depression of the rear ends of the members, and a yieldable support upon which said members are rockably 60 mounted.

3. In a typewriting machine, a sheet-metal rock-shaft pivotally supported at the rear of the platen and adapted to have its front edge tilted downwardly, a paper feed-roll frame and means whereby the tilting of said 70 shaft moves said feed-roll frame away from the platen.

4. In a typewriting machine, a rockable sheet-metal bar or plate arranged at the rear of the platen provided with forwardly-extending integral fingers, and a movable feed-roll frame adapted to be depressed by said 75 fingers.

5. In a paper feed mechanism, the combination of a platen, a support for the platen, tandem feed-roll shafts, feed rolls on said shafts, tilttable supporting means for the shafts spring-urged toward the platen, a manually rockable part provided with upwardly facing hook-like members through 80 which the rear feed-roll shaft extends and adapted to exert downward pressure on the shaft-supporting means adjacent the rear shaft to tilt said means, and upstanding members on said shaft-supporting means 85 normally spaced from said rockable part and adapted to be engaged thereby to lock the shaft-supporting means to rock with said part after an initial tilting of said means by said hook-like members.

6. In a typewriting machine, a platen-carriage having upright end flanges, a sheet-metal rockable plate or bar extending between said flanges and having integral ears at its ends, pivots connecting said ears to said end flanges, means for rocking said plate-like shaft, feed-rolls, and means whereby the rocking of the shaft releases the feed-rolls.

7. In a paper feed mechanism, the combination of a platen, a support for the platen, tandem feed-roll shafts, feed rolls on said shafts, bars extending transversely of the platen in which said shafts are journaled, a spring-pressed member extending longitudinally of the platen and loosely engaging under said bars intermediate the feed-roll shafts, and manually rockable means coacting with said bars adjacent one of said feed-roll shafts when said means is rocked in one direction for first swinging the bars about the other feed-roll shaft and then swinging the bars bodily with said rockable means and continuously forcing said spring-pressed member away from the platen.

8. In a typewriting machine, the combination of a platen-carriage, a platen rotatably mounted on the carriage, a pair of paper-feed-rolls spaced apart circumferentially of the platen, means for rotatably supporting the rolls in spaced relation, spring-pressed means on the carriage normally forcing said roll-supporting means toward the platen, a rock-shaft journaled on the 125 130

- carriage, and means connecting the rock-shaft to the roll-supporting means for swinging the supporting means first about an axis coincident with the axis of one feed-
5 roll and then about the axis of the rock-shaft against the pressure of the spring-pressed means.
9. In a typewriting machine of the class set forth, a platen-carriage, a roller platen 10 on the carriage, a rock-shaft journaled on the carriage arranged at the rear of the platen and provided with a plurality of forwardly-extending hooks, a frame lying under the platen, a set of front and rear 15 feed-rolls carried by the frame, and means for moving said frame toward the platen, the shaft of the rear feed-rolls engaging in said hooks.
10. In a typewriting machine of the class set forth, a rock-shaft at the rear of the platen provided with two pairs of forwardly-extending hooks, two sets of feed-rollers 20 each embodying a front-shaft and a rear-shaft and transversely-extending connecting bars, said bars and shafts forming a frame, and each of said rear-shafts engaging in a 25 pair of said hooks, for the purpose herein set forth.
11. In a typewriting machine of the class set forth, a rock-shaft at the rear of the platen provided with downwardly-bent 30 hooks opening upwardly, a normally pressed-up feed-roll frame adapted to be tilted downwardly at its rear edge by said hooks when said rock-shaft is rocked forwardly, and a rear feed-roll shaft carrying 35 feed-rolls and engaging in said hooks, for the purpose set forth.
12. In a typewriting machine of the class set forth, a sheet-metal rock-shaft extending 40 the length of the platen and having an integral forwardly-extending arm lying flatwise against one end of the platen-frame, a lever for rocking the rock-shaft pivoted adjacent to the aforesaid arm and adapted to 45 contact therewith to rock the rock-shaft, a spring for holding the rock-shaft and its arm in normal position against said lever, and means whereby when said rock-shaft is 50 rocked the paper-feed devices are released.
13. In a typewriting machine of the class set forth, a platen-carriage, a roller platen 55 on the carriage, a set of feed-rolls embodying a rear-shaft and feed-rolls and a frame in which said shaft is journaled to have an endwise play, and a rock-shaft journaled on the carriage at the rear of the platen and provided with a forwardly-extending finger or ear adapted to arrest endwise movement 60 of said feed-roll shaft.
14. In a typewriting machine of the class set forth, two sets of feed-rolls and a vertically-movable frame for each, each frame embodying a rear feed-roll shaft having an 65 endwise play in said frame, and a rock- shaft for releasing said feed-rolls from the platen and provided with a pair of stops projecting forwardly and lying adjacent to the outer ends of said feed-roll shafts to prevent undue endwise play thereof. 70
15. In a paper feed mechanism, the combination of a platen, a pair of feed-roll frames arranged end to end and each comprising a pair of end bars having upstanding apertured ears adjacent each end of the bars and front and rear feed-roll shafts journaled in the apertured ears on each pair of bars and removable endwise, feed-rolls on said shafts, a manually rockable device cooperating with the end bars to 75 shift the feed-rolls away from the platen and separably interlocked with the feed-roll frames through the medium of the rear feed-roll shafts, bendable parts on said rockable device for holding the rear feed-roll 80 shafts against withdrawal from their bearing ears, and bendable parts on the end bars for holding the front feed roll shafts against withdrawal from their bearing ears. 85
16. In a typewriting machine, the combination of a platen-carriage, a roller platen on the carriage, a feed-roll-frame embodying bars extending transversely under the platen and front and rear feed-roll-shafts supported on said bars, feed-rolls on the roll-shafts, and a roll-cast-off rock-shaft provided with rock-arms coacting with said bars to cast-off the feed-rolls, said rock-arms being interlocked with the rear ends of the bars to prevent undue endwise movement of the feed-roll-frame and having a pivoted connection with the rear feed-roll-shaft adapted to permit vertical movement of the feed-roll-shaft relatively to said arms when the cast-off rock-shaft is in normal position. 90
17. In a paper feed mechanism, the combination of a platen, a pair of tandem feed-roll shafts, feed-rolls on said shafts, end members extending transversely of the platen in which said shafts are journaled, manually rockable means for shifting said shafts and members away from the platen interlocked with said end members and the rear feed-roll shaft to permit up-and-down 100 movement of the shafts and members independently of said rockable means and restrain movement thereof longitudinally and transversely of the platen, and means for yieldably urging said members and shafts 105 toward the platen. 110
18. In a paper feed mechanism, the combination of a platen carriage, a platen supported in the carriage, a feed-roll frame, front and rear feed rolls on the frame, yieldable means urging the frame toward the platen, a rock-shaft having a flat face journaled on the carriage at the rear of the frame, means for rocking said shaft, forwardly extending arms carried by said shaft 125 130

- adapted to press downwardly on the frame adjacent the rear feed-roll and depress the rear part of the frame when said shaft is rocked in one direction, and arms on the rear of the frame normally spaced from the flat face of the rock-shaft and adapted to be engaged by said flat face upon further rocking of the shaft in the same direction to lower the forward part of the frame.
19. In a typewriting machine of the class set forth, a rear rock-shaft journaled beyond the rear side of the platen, a tiltable frame embodying front and rear feed-rolls located between the platen and its bed-plate, and means whereby the rocking of said shaft will first tilt the rear rolls away from the platen and subsequently tilt the front rolls away from the platen, said means embodying devices carried by the rock-shaft and adapted to engage the rear edge of said frame and devices carried by said frame adapted to engage the rock-shaft to impart the final tilting movement.
20. In a paper feed mechanism, the combination of a platen, members extending transversely of the platen, front and rear feed-roll shafts supported by said members, feed rolls on the shafts, a rock shaft, rock arms on said shaft having depending U-shaped forward end portions embracing the rear feed roll shaft and overhanging the rear ends of the transverse members, means for rocking said shaft to depress the rear ends of the transverse members through the medium of said rock-arms, and means on said transverse members adapted to engage over the rock shaft after depression of the rear ends of the members to cause the members and rock shaft to swing as a unit about the axis of oscillation of the rock shaft, and spring-urged means loosely engaging under said transverse members intermediate the feed-roll shafts.
21. In a typewriting machine, the combination of a platen-carriage, a roller platen on the carriage, a feed-roll-frame under the platen, yieldable means on the carriage for normally pressing the frame toward the platen, front and rear feed-rolls on the frame, and rockable cast-off means on the carriage adapted when rocked in one direction to first engage and depress the rear part of the frame and subsequently also engage the frame at a different point to cause the frame to rock bodily with said rockable means during a further movement of said means in the same direction.
22. In a type writing machine of the class set forth, a platen-carriage, a roller platen on the carriage, two feed-roll frames, each embodying a front-shaft carrying a feed-roll and a rear-shaft carrying a feed-roll, means on the carriage for normally pressing said frames toward the platen, and means for forcibly pressing said frames with

their rolls away from the platen, said means embodying a rock-shaft journaled on the carriage carrying fingers which engage the rear edges of each of the frames at its opposite ends so as to tilt the rear edges of the frames downwardly, and means cooperating between the frame and the rock-shaft for subsequently forcing the front edges of the frames away from the platen.

23. In a typewriting machine of the class set forth, a platen-carriage, a platen rotatably mounted on the carriage, a feed-roll frame embodying a pair of transverse bars and roll-shafts connecting the ends thereof, a longitudinal bar extending underneath said transverse bars, a supporting device mounted on the carriage underneath the center of said longitudinal bar, and means for normally pressing said supporting device toward the platen, the ends of said longitudinal bar having a rockable connection with the transverse bars and its center having a connection with said supporting device rockable on a transverse axis.

24. In a typewriting machine of the class set forth, a platen-carriage, a platen rotatably mounted on the carriage, a feed-roll frame embodying a pair of transverse bars and roll-shafts connecting the ends thereof, a longitudinal bar extending underneath said transverse bars, a supporting device mounted on the carriage underneath the center of said longitudinal bar, and means for normally pressing said supporting device toward the platen, said transverse bars 100 and said longitudinal bar being flat and having a loose flatwise bearing upon each other, for the purpose set forth.

25. In a typewriting machine of the class set forth, a platen-carriage, a roller platen 105 on the carriage, a feed-roll frame embodying feed-rolls and a pair of transverse flat bars provided with bearings for the shafts of said feed-rolls, a longitudinal flat bar arranged between the base of the platen carriage and said flat bars and having its ends engaging flatwise against the under side of said transverse bars, and means for normally pressing said longitudinal bar toward the platen.

26. In a type-writing machine of the class set forth, a platen-carriage, a roller platen on the carriage, a feed-roll frame embodying feed-rolls and a pair of transverse flat bars provided with bearings for the shafts of 120 said feed-rolls, a longitudinal flat bar arranged between the base of the platen carriage and said flat bars and having its ends engaging flatwise against the under side of said transverse bars, and means for normally pressing said longitudinal bar toward the platen, said means embodying a flat plate arranged transversely of the platen and adapted to support the longitudinal bar approximately at its mid-length, and spring 125 130

means normally tending to press said flat plate toward the platen, whereby when the feed-rolls are moved to released position said bar and said plate lie flatwise against the top-face of the platen-carriage.

27. In a typewriting machine of the class set forth, a platen-carriage, a roller platen on the carriage, a feed-roll frame embodying front and rear shafts carrying the feed-rolls, transverse bars provided with journals at their ends for the ends of said feed-roll-shafts, a longitudinal bar engaging said transverse bars, and means for normally pressing said longitudinal bar toward the platen to thereby normally tend to force the feed-rolls into feeding position, said means embodying a rockable plate mounted on the carriage underneath said longitudinal bar provided with an opening, said longitudinal bar being provided with laterally-extending hooks extending down through said opening to thereby lock the plate to the bar but permit limited independent rocking motion of the bar and the plate.

28. In a typewriting machine of the class set forth, a platen-carriage, a roller platen on the carriage, a pair of feed-roll frames each embodying a feed-roll-shaft and a pair of transverse bars supporting the ends of said shafts, means for independently pressing said frames toward the platen embodying a sheet-metal longitudinal bar arranged underneath each frame and adapted to have its ends engage under said transverse bars, a sheet-metal rockable supporting plate mounted on the carriage under the center of each longitudinal bar and having a loose rocking connection therewith, and means for normally swinging said supporting and rocking plates toward the platen, said longitudinal bars and said rocking plates being arranged flatwise with reference to each other so as to lie closely adjacent to each other and the base of the platen-carriage when the feed-rolls are moved to released position.

29. In a typewriting machine, a platen-carriage, a platen on the carriage, a paper-feed mechanism embodying two separate frames each having a front feed-roll-shaft carrying a pair of feed-rolls, a paper-guide having two depending ears adjacent opposite ends thereof each pivotally connected to the outer end of one of said shafts, and means for depressing said shafts to take the rolls and guide away from the platen.

30. In a typewriting machine, a platen-carriage and a shaft mounted therein carrying a platen, a paper-feed-roll arrangement embodying a rock-shaft, this rock-shaft being provided with an arm, and a cam-lever for rocking said shaft through the medium of said arm, said cam-lever having its bearing on said platen-shaft.

31. In a typewriting machine, a rock-

shaft journaled in the platen-carriage, a feed-roll-frame having a feed-roll shaft at its rear edge supported entirely by the frame and hingedly engaging said rock-shaft, said rock-shaft being provided with a lug which serves to lock said feed-roll shaft to said feed-roll-frame and the rock-shaft.

32. In a typewriting machine, a paper-feed-frame having transverse bars provided at their rear-ends each with two upturned lugs having alined shaft-holes and each being also provided with upstanding integral lugs at their forward ends also provided with shaft-holes, feed-roll-shafts journaled in the holes in said lugs, means independent of the rear feed-roll-shafts for preventing undue endwise movement of the rear-shafts, and upstanding lugs on the forward ends of the transverse bars for preventing undue endwise movement of the front-shafts.

33. In a typewriting machine, a paper-feed-roll mechanism embodying a rock-shaft having at one end a forwardly-projecting integral arm curved laterally between its free end and its connection to said rock-shaft, a feed-roll-frame connected to said rock-shaft and having a rear feed-roll-shaft slideable endwise out of its bearing, this shaft being in alinement with the curved part of said arm so that said shaft may be drawn out endwise without striking against said lever.

34. In a typewriting machine, the combination of a platen-carriage, a platen on the carriage, a feed-roll-frame, tandem feed-rolls on the frame, and means mounted on the platen-carriage yieldably pressing the frame toward the platen, said means embodying a bar arranged longitudinally with respect to the platen and bearing against said frame at its ends, a member on the carriage rockable about an axis extending transversely of the carriage, said bar being mounted on said member intermediate the ends of the bar to rock about an axis extending transversely of the carriage, and spring means for rocking said member toward the platen.

35. In a typewriting machine, a platen-carriage, a platen on the carriage, front and rear paper-feed-rolls, a frame supporting the rolls including transverse bars, a longitudinal bar having its ends pressing upwardly against the under side of said transverse bars, a transversely-rocking member mounted in the platen-carriage, said longitudinal bar being connected at a point approximately midway between its ends to said transverse member to rock about an axis extending transversely of the bar, and spring means tending to force said rocking member toward the platen, whereby the feed-roll-supporting-frame may yield bodily toward and away from the platen while in action

and may also tilt both sidewise and endwise with respect to the platen while in action.

36. In a typewriting machine, a platen-carriage, a platen on the carriage, a feed-roll-carrying-frame, tandem feed-rolls in the frame, a longitudinal bar arranged between the platen and the base of the platen-carriage for pressing said frame toward the platen, said bar being enlarged laterally at 10 a point approximately midway its length and provided at the ends of said enlargement with depending hooks, a rocking member mounted on the platen-carriage and provided with an opening for the reception 15 of said hooks to thereby rockingly connect this member with said longitudinal bar, and spring means for normally pressing the rocking member upwardly toward the platen.

20 37. In a typewriting machine, a platen-carriage, a platen on the carriage, a feed-roll-carrying-frame, tandem feed-rolls in the frame, a longitudinal bar arranged between the platen and the base of the platen-carriage for pressing said frame toward the platen, said bar being enlarged laterally at 25 a point approximately midway its length and provided at the ends of said enlargement with depending hooks, a rocking member mounted on the platen-carriage and provided with an opening for the reception of 30 said hooks to thereby rockingly connect this member with said longitudinal bar, and spring means for normally pressing the rocking member upwardly toward the platen, said longitudinal bar being flat in 35 cross-section and said rocking member being likewise flat in cross-section, whereby said bar and said rocking member may lie 40 close against the base of the platen-carriage when they are depressed to release the rolls.

38. In a typewriting machine, a platen-carriage, a platen on the carriage, a pair of feed-roll-frames arranged end to end on the 45 carriage, means for positively forcing the frames away from the platen, and collapsible spring-urged means for resiliently pressing said frames toward the platen pivotally mounted on the platen-carriage and 50 adapted to lie flat against the said frames when the frames are forced away from the platen.

39. In a paper feed mechanism, the combination of a platen carriage, a platen thereon, a pair of feed-roll frames arranged end to end along the platen, tandem feed rolls in each frame, a pair of rockable members pivotally held to the carriage to rock toward and from the platen about axes extending transversely of the platen, a single spring connected at its opposite ends with 55 said rockable members and normally urg-

ing the members toward the platen, and a pair of pressure-distributors rockably mounted intermediate their ends on said 65 rockable members and each extending longitudinally of a different frame and pressing there-against substantially midway between the tandem feed rolls in the frame.

40. In a typewriting machine, a platen-carriage, a platen on the carriage, a feed-roll-frame and means for depressing it away from the platen embodying a rock-shaft journaled on the carriage made of sheet-metal and having a flat top-plate and a rear 70 depending plate, and means for normally pressing the feed-roll-frame toward the platen embodying a coil-spring arranged longitudinally of the platen and housed in the angle formed by the plates forming the 75 rock-shaft.

41. In a paper feed mechanism, the combination of a platen carriage, a platen thereon, a plurality of feed-roll frames, tandem feed-rolls in the frames, a plurality of 80 spring-urged devices mounted on the carriage and normally urged toward the platen, and members fulcrumed on said devices and each supporting a different 85 one of said frames to tilt therewith away from the platen at two opposite sides of the frame and to tilt relatively to said member to permit either of the other two sides of the 90 frame to move away from the platen.

42. In a paper feed mechanism, the combination of a platen carriage, a platen thereon, a plurality of feed-roll frames, tandem feed-rolls in the frames, a plurality of 95 spring-urged devices mounted on the carriage and normally urged toward the platen, members fulcrumed on said devices and each supporting a different one of said frames to tilt therewith away from the platen at two opposite sides of the frame and to tilt relatively to said member to permit either of the other two sides of the 100 frame to move away from the platen, and a single spring urging all of said devices toward the platen.

43. In a paper feed mechanism, the combination of a platen carriage, a platen on the carriage, a spring-urged device mounted on the carriage and normally forced toward the platen, a tiltable member pivoted on said device intermediate its ends, a feed-roll frame, and tandem feed-rolls in the frame, said frame being supported on said 110 tiltable member to rock thereon about an axis extending transversely of the pivotal axis of the tiltable member.

This specification signed this sixteenth day of September, A. D., 1918.

FRANK HURBERT ARMSTRONG.
